UNITED STATES PATENT OFFICE.

GRAY STAUNTON, OF CHICAGO, ILLINOIS.

VALVE FOR HERMETICALLY-CLOSABLE JARS.

No. 873,627.

Specification of Letters Patent.

Patented Dec. 10, 1907.

Original application filed September 22, 1905, Serial No. 279,630. Divided and this application filed April 2, 1906. Serial No. 309,303.

To all whom it may concern:

Be it known that I, GRAY STAUNTON, a citizen of the United States, residing at Chicago, in the county of Cook and State of Illinois, 5 have invented certain new and useful Improvements in Valves for Hermetically-Closable Jars, of which the following is a specification.

My invention relates to valves for hermetically closable jars and other vessels, and has for its primary object to provide a valve arrangement which will be simple in construction, easy of application, efficient and reliable in operation and cheap of manufacture.

10 To these and other ends it should become apparent to those skilled in the art, my invention consists in the features of construction and combination and arrangement of parts hereinafter more fully set forth and 15 specified in the claims.

In the drawings, wherein I have illustrated an operative embodiment of my invention, and parts of the completed structure; Figure 1 is a central vertical section of a jar, having applied thereto a closure embodying my invention. Fig. 2 is a cross sectional detail of a portion of the closure structure showing the valve. Fig. 3 is a side elevation of the valve detached, and, Fig. 4 is a plan view 30 thereof, in inverted position.

Throughout the figures like numerals of reference refer always to like parts.

In the drawing 10 indicates a vessel of any suitable size and configuration, the vessel 35 shown having an open mouth 10' as is common in preserving glasses and the like to be purchased on the market.

11 indicates in general the body of the closure which is preferably made of glass of 40 suitable thickness, with which is suitably associated a sealing ring 16 adapted and arranged for coaction with the open mouth of the receptacle body 10 to form a hermetic joint between the body and closure. So far 45 as the present invention is concerned the seal ring may be of any desired character, but that which I have herein shown by way of illustration is specifically described and claimed in my co-pending application, filed 50 September 22nd, 1905, bearing Serial No. 279,630, whereof this application is a division.

At some suitable point in the package 55 formed by the associated vessel and closure, preferably centrally of the closure member thereof, is located a vent opening 13, prefer-

ably communicating on the underside of the closure with a recess 14, and at its upper side with a suitable recess 15, preferably circular in plan and preferably also having a flat bottom surface as indicated at 15'.

60 A valve, generally indicated at 17, is preferably constructed of rubber, and in the specific embodiment shown comprises an umbrella-shaped head or valve proper 18, tapering from the center outward, and normally of convexo concave shape, as shown in Fig. 2, a central boss 18' upon said head; a stem or shank 19 integrally connected with the said head; and flexible spurs 20 projecting from 65 the stem at the bottom thereof. Preferably the valve is of a height over all not in excess of the thickness of the closure 11, so that the valve may sit wholly within the recesses 14 and 15 and the vent aperture 13 70 of the closure. The shank of the valve should be somewhat greater in length than the thickness of the wall intermediate the recesses 14 and 15 of the closure, so as to allow of slight vertical movement of the 75 valve; and said stem is of less diameter than the vent opening 13. The boss 18' upon the head is preferably about the size of the vent opening.

80 The valve described, in use, is inserted in place in the closure by compressing or distorting the flexible spurs 20 and forcing them and the valve stem through the vent opening 13, so that the umbrella-shaped head of the valve lies wholly within the recess 15 and the spurs protrude from the shank within the confines of the recess 14 formed therefor in the bottom of the closure. 85 The spurs 20 may readily be so constructed that they resist removal of the valve with sufficient force to prevent its disengagement 90 from the closure during any normal operation of handling the closures, but permit of the ready disengagement of the valve from the closure when it is intentionally sought to 95 remove the same.

100 The operation of my improved device is as follows: When it is desired to hermetically seal the vessel, the closure is applied to the open end thereof and the air exhausted from the interior of the vessel. This may be done either by heating the vessel, thereby causing its contents to expand and a portion of the air to force its way through the vent opening, and subsequently permitting the 110 vessel to cool, in order that the air may contract therein and produce a vacuum tendency.

which effects the seating of the valve, or by mechanical exhaustion of the air or by proper combination of both processes. In the event of any exhaustion of the air the 5 resultant tendency to a vacuum effects the seating of the valve and closure upon their respective seating surfaces. In the drawings I have shown at 21 a fragment of an exhaust pump and it will be understood that 10 by such means air may be drawn from the vent opening 13, the valve rising with each suction stroke of the plunger, thereby decreasing the pressure within the vessel, so that the overbalancing exterior air pressure 15 forces the closure 11 tightly upon the vessel 10, compressing to some extent the sealing ring 16, and at each down stroke of the pump plunger the valve 17 seating upon its flat surface 15' with considerable force. It will 20 be apparent now that when the valve 17 is thus forcibly seated, the central portion of its umbrella head, crowding under pressure against the edges of the vent aperture 13 as shown in Fig. 2, causes the flattening of the 25 normally cup-shaped umbrella, and the consequent expansion, to a slight extent, of the thin peripheral edge of the head. This flattening of the cup-shaped head causes its edge portion to press tightly against the seating 30 surface 15' therebelow, and to force an effective and air tight joint by which slight irregularities in the seating surface are compensated for. Furthermore the boss 18 tends to wedge the rubber tightly in the 35 opening 13, to make a tight fit with the edges of the vent.

While I have herein described in some detail a specific embodiment of and manner of combination of the parts of my invention, 40 which I deem to be novel and advantageous, it will be apparent that slight changes might be made in the construction and arrangement without departure from the spirit and scope of my invention. It will further be 45 apparent that while I have shown glass as a material of which the vessel and closure body are made they might be made of any hard, impervious material, and that the invention herein disclosed is adapted to a vessel or 50 closure of any size or shape.

Having thus described my invention, what I claim and desire to secure by Letters Patent, of the United States, is:

1. In combination, a vessel, a closure 55 therefor, said closure having a vent opening therein, and a valve arranged for coaction with said vent opening comprising a stem extending through the vent opening, and a convexo concave head overlying the area 60 surrounding the vent opening.

2. In combination, with a package to be sealed, having a vent opening in a suitable part, a valve for closing said vent opening, comprising a convexo concave member of

elastic material, adapted and arranged when 65 in closing position to overlie said vent.

3. In combination with a package to be hermetically sealed, having a vent opening therein, a valve for said vent opening comprising a body of convexo concave shape 70 tapering from its center toward its edge, and composed of resilient material, said valve being arranged to overlie the portion of the package surrounding said vent opening.

4. In a closure for vessels, a body portion 75 having a vent opening therein, a rubber valve therefor having a convexo concave shape in cross section.

5. A closure for jars comprising a body having a vent opening therein, a valve for 80 closing said vent opening comprising a stem extending through the opening, and a convexo concave head of generally circular shape arranged to overlie the portion of the closure surrounding the vent opening, said 85 valve head being of resilient material.

6. A closure for vessels comprising a body having a vent opening therein, and a rubber valve for said vent opening of convexo concave shape, tapering toward its outer edge 90 and generally circular in plan, and means for retaining said valve in position upon the closure body.

7. In a closure for vessels, a body having opposing recesses therein connected by a 95 vent opening and a valve of flexible, elastic material substantially contained within the recesses, comprising a head of umbrella shape convexo concave in cross section and tapering toward its outer edge, arranged in 100 one recess, a stem extending through the vent opening, and flexible retaining means extending into the opposite recess.

8. In a closure for vessels, a body portion having a vent opening therein, a rubber 105 valve for said vent opening comprising an umbrella head, a shank extending into the vent opening, and a boss alining with said shank in the opposite side of the head.

9. In combination with a package to be 110 hermetically sealed, having a vent opening therein, a rubber valve having a concave under surface arranged to cover the vent opening.

10. In combination, a package to be hermetically sealed, having a vent opening in a suitable part thereof, and a rubber valve therefor comprising a convexo concave head overlying the vent, a stem extending through said vent, and a retaining means on the end 120 of the stem.

In testimony whereof I hereunto set my hand in the presence of two witnesses.

GRAY STAUNTON.
